UNITED STATES PATENT OFFICE.

CHARLES E. MARTIN, OF MANSFIELD, OHIO.

ROOF FOR SILOS OR THE LIKE.

1,096,442.

Specification of Letters Patent.

Patented May 12, 1914.

Application filed February 21, 1913. Serial No. 749,910.

To all whom it may concern:

Be it known that I, CHARLES E. MARTIN, a citizen of the United States of America, residing at Mansfield, in the county of Rich-
5 land and State of Ohio, have invented cer-
tain new and useful Improvements in Roofs
for Silos or the like, of which the follow-
ing is a specification.

This invention relates to certain new and
10 useful improvements in roofs for silos or
the like, and is an improvement on Letters
Patent No. 1,082,012, granted to me July 9,
1912.

The primary object of the present inven-
15 tion is to provide a roof of the type set
forth, in which the opening of the roof is
covered by a member which can be easily
and quickly moved to cover or uncover the
20 opening, and to this end the invention re-
sides in new and improved means for con-
necting the member to the roof structure in
such way that its operation as above set
forth can be effected.

In my prior patent the objection is pre-
25 sented of possible corrosion of the ring
which is movably mounted on the venti-
lator body, making it difficult to shift the
closure member to which the ring is secured,
30 in covering and uncovering the roof open-
ing. The present invention therefore aims
to provide means for connecting the closure
member to the roof structure, whereby the
aforementioned objection is overcome.

In the drawings: Figure 1 is a fragmen-
35 tary side elevation of a silo and the roof
structure thereof; and Fig. 2 is a detailed
top plan view of the ventilator, which latter
is partly broken away, showing the means
40 for connecting the closure member to said
ventilator.

The silo body 1 has a conical corrugated
45 roof 2, which latter is provided with an
opening 3, a ventilator 4 being attached
to the apex of the roof and being of any
approved form, all of which aforemen-
50 tioned parts are disclosed in my prior patent
above mentioned. The closure member 5 is
formed of a corrugated section of metal and
has its inner end pivotally secured by means
of a pivotal pin 6 to the lower leaf 7 of a
hinge 8, the upper leaf 9 of which hinge is
rigidly secured by rivets 10 to the body of
the ventilator 4. The hinge therefore has no
lateral movement, but is stationary with re-

lation to the roof structure, while the clo-
sure member 5 is not only movable laterally
of the roof structure, but is also movable
vertically in the plane of an arc. As shown
in Fig. 2 of the drawings the closure mem-
ber 5 can be moved from the full to the dot-
ted line position about the pivot pin 6, and
since the latter presents such an extremely
small surface subject to corrosion, it will be
evident that the possibility of such corro-
sion is reduced to a minimum, and in any
event should corrosion take place, to and fro
lateral movement of the closure member 5
would readily remove the corrosion and
allow the desired easy movement of the
member 5. In addition the means disclosed
in the present invention presents the advan-
tages of simplicity, economy in material,
and consequent reduction in the cost of man-
ufacture of the means disclosed in my
aforementioned patent, aside from the other
advantages hereinbefore set forth.

What is claimed is:

1. In combination with the roof structure
of silos or the like, comprised of a series of
overlapping tapered corrugated sections
which roof has an opening, and a pivotal
closure member for the opening, single hori-
zontal pivotal means for connecting the clo-
sure member to the roof consisting of a
hinge having one leaf rigidly secured to the
roof structure, and having its other leaf piv-
otally secured to the closure member by a
single vertical pivot whereby the latter may
be moved vertically with respect to the roof
and laterally thereof about said single
pivots.

2. In combination with a roof structure of
silos or the like, comprised of a series of
overlapping tapered corrugated sections
which roof has an opening, and a closure
member for said opening, single horizontal
pivotal means for hingedly connecting said
closure member to the roof and single verti-
cal means for pivotally connecting the clo-
sure member to said means to allow the clo-
sure member to move vertically of the roof
and laterally thereof as well, said vertical
and lateral movements being accomplished
by single pivots.

3. In combination with a roof structure of
silos or the like, comprised of a series of
overlapping tapered corrugated sections
which roof has an opening, and a combined

vertical and horizontal pivotal closure member for said opening, a single horizontal pivot to hingedly connect said closure member to the roof structure and a single vertical pivot whereby the closure member may have lateral movement independent of said hinged means as described and set forth.

In testimony whereof I affix my signature in presence of two witnesses.

CHARLES E. MARTIN.
